UNITED STATES PATENT OFFICE.

WILLIAM H. RITTS, OF ETNA, PENNSYLVANIA, ASSIGNOR TO GEORGE T. LADD, OF PITTSBURGH, PENNSYLVANIA.

BOILER.

1,258,248.

Specification of Letters Patent.

Patented Mar. 5, 1918.

Application filed February 28, 1916. Serial No. 80,912.

To all whom it may concern:

Be it known that I, WILLIAM H. RITTS, residing at Etna, in the county of Allegheny and State of Pennsylvania, citizen of the United States, have invented or discovered certain new and useful Improvements in Boilers, of which improvements the following is a specification.

In order to obtain efficiently the maximum capacity of a boiler, it is necessary to secure not only a maximum combustion of coal per square foot of grate area, but also a complete combustion of combustible gases and solids, and to so apply the heat units, thus obtained, to the boiler tubes as to avoid excessive local heating and insure a uniform heating of the tube surfaces. A maximum combustion per foot of grate area is best obtained by the employment of under-feed stokers and a forced draft, the air being directed through the coal into the bed of fire. The results that may be expected from the employment of stoking mechanism and forced draft has not been obtained for the reason that provision was not made for the complete combustion of the increased quantities of gases, etc., generated before the same come in contact with the tubes and boiler proper. As for example, the combustion chamber was not made of sufficient size to afford the space for such expansion as is necessary for complete combustion of gases, the exits from the combustion chamber being restricted and so located that the gases are brought into contact with the cold surfaces of the water tubes before complete combustion has occurred and are thereby so cooled that further combustion is impossible. It has been attempted to relieve the congestion in the combustion chamber by employing a high stack to increase the rate of flow of the gases from the chamber, but it was found that the gases flowed too rapidly through the fire-box to permit complete combustion.

As for example, it has heretofore been the custom to employ a combustion chamber having a height not substantially greater than one-third and in some cases one-half of the height of the chamber in which the boiler proper is located. In such cases the front wall rising above the top of the fire-box, is but a comparatively short distance away from the first set of tubes and with the usual arrangement of baffling, having tiles

located along the rear line of tubes from the first set or bank adjacent to the fire-box. The passage of the products of combustion from the fire-box to the upper end of the tubes is narrow and being nearly filled with tubes of the first bank, the flow of gases from the fire-box is restricted. When employing a forced draft, gases are generated more rapidly than under normal draft conditions, and in order to relieve the congestion of the fire-box, the pull of the stack is increased, thereby causing the products of combustion to move so rapidly that sufficient transmission of heat to the tubes is impracticable, unless the number of passages are increased with consequent greater draft losses. In the construction above described, the gases are brought into contact with relatively cold tubes before complete combustion can occur.

It is the object of the invention described herein to provide a fire-box or combustion chamber of sufficient size and of such transverse shape as will permit of the natural upward movement of the gases from the grate and their expansion, thus promoting combustion of all gases and finely divided solid material carried up by the gases, said combustion chamber being so disposed relative to the first bank of tubes that they will be uniformly heated from end to end and all local heating avoided. It is a further object of the invention to provide for the feeding of fuel into the furnace at a point remote from the heating surfaces of the boiler in order that the gases formed in the combustion of the fuel may be consumed before coming into contact with the surfaces that will cool or tend to cool the gases below temperatures at which combustion of the gases can occur. The invention is herein-after more fully described and claimed.

In the accompanying drawings forming a part of this specification, the figure is a sectional elevation of a vertical water-tube boiler in combination with my improved fire-box and combustion chamber, the plane of section being at right angles to the axes of the drums.

Given means whereby a maximum combustion of fuel per square foot of grate area may be obtained, effective utilization of such combustion is dependent upon a complete combustion of gases generated and small particles of solid fuel carried by the gases

and an even uniform application of the heat generated by such combustion to the heating surfaces. The first condition can be fulfilled by affording opportunity for the gases to 5 expand and freely intermingle, and avoiding any material cooling or chilling of any considerable portion of the gases below a temperature at which complete combustion will occur and the regeneration of such 10 per centages as may be cooled.

The second condition can be fulfilled by causing portions of the gases to flow uniformly along the tubes from end to end while combustion is being completed and to 15 insure the flow of gases subsequent to such complete combustion, along the entire length of tubes during such pass among the tubes. Care should be taken that the flow of gases should not be restricted or diverted in any 20 such manner as will tend to cause an excessive heating of the tubes at any point.

In the practice of the invention, the boiler proper consisting of upper and lower drums 1 and 2 and vertical connecting tubes, which 25 are preferably separated into a plurality of sets of banks, as 3, 4, and 5, is arranged in a setting of the usual combination having back and side walls 6 and 7 closely adjacent to the boiler proper. The combined 30 fire box and combustion chamber is made of a height approximately equal to the distance between the upper and lower drums and of substantially uniform depth for its entire height and of a width substantially equal to 35 the width of the boiler. The rear wall of the combined fire-box and combustion chamber is formed by the first bank of tubes and the baffle 8 arranged therein, and the upper and lower portions of the respective drums. 40 Fuel is fed by a suitable form of stoking mechanism indicated at 12, for the entire width of the fire-box, air, preferably under pressure, being admitted under the grate 10 through a pipe 11. As hereinbefore stated, 45 provision should be made for so feeding the fuel into the furnace that gases formed by the combustion of the fuel will not be cooled before complete combustion can occur. In the construction shown, the stoking mechanism is arranged to feed the fuel through 50 the front wall of the fire box or wall most distant from the first bank of tubes and hence the gases generated by the combustion of the fuel on the grate surfaces will flow 55 directly upward and will not contact with any of the relatively cool heating surfaces until opportunity has been afforded for a complete combustion of such gases.

In such a combined fire-box and combustion chamber, the gases will rise up vertically from the points where formed. The gases which come into contact with the tubes of the first bank of tubes will be cooled to a greater or less degree and this cooling will 60 65 tend to cause a downward flow along the

tubes of the first bank. The gases thus flowing downward will be deflected outward into the gases moving up from the fuel bed, and be regenerated by such hot gases. The gases thus deflected will so modify the action of 70 the hot gases on the lower portions of the tubes as to prevent excessive heating.

In operating the boiler, provided the same is properly baffled, the pull of the stack will not materially accelerate the upward movement of the gases in the combustion chamber and will afford ample opportunity at all times for complete combustion and a thorough mixing of the gases by the circulation due to contact and cooling of the gases 80 with the first bank of tubes as hereinbefore stated.

The provision herein before described for insuring complete combustion and avoiding local heating of the tubes of the first bank 85 of tubes, would be supplemented by insuring a uniform travel of the gases in the subsequent passes. To this end, the throat between the upper end of the baffle 8 and the upper drum should extend the entire width 90 of the boiler and be of such a depth as not to materially restrict the flow of gases therethrough and the throats connecting other passes are preferably similarly proportioned, but may be made of slightly less depth as 95 the rate of travel of the gases can be maintained by the pull of the stack, the volume of the gases being reduced by cooling and hence some lessening of the depths of successive throats would not cause any congestion 100 in the preceding passes.

After passing through the throat above the baffle 8, the products of combustion flow down through the chamber or space in which the second set of tubes 4 is arranged intermediate the baffle 8 and the baffle 9 arranged in the rear of the second set or bank of tubes 4. In leaving this space or chamber, the gases pass across the lower portions of the sets of tubes 4 and 5 and through the 110 space or chamber intermediate the baffle 9 and the rear wall of the boiler setting, and occupied by the third set of tubes 5.

In boilers as heretofore constructed, the fire box has been so constructed and arranged as to cause a restriction of the flow of hot gases from the fire-box and a local 115 excessive heating of the tubes as hereinbefore stated; such injurious heating is due not only to contact of hot gases, but also to 120 the heat radiated from the walls of the fire box and concentrated by reason of their shape and the relation of their surfaces to the tubes at the point of restriction of the products of combustion flowing from the 125 fire-box.

In the improved construction shown herein, having the walls and combined fire box and combustion chamber substantially parallel with the tubes, the heat radiating from 130

such walls will be as evenly distributed along the entire length of the tubes as the heat derived from the gases flowing up from the combustion chamber.

5 I claim herein as my invention:

1. The combination with a boiler consisting of an upper and a lower drum, and a plurality of sets or banks of tubes connecting said drums, baffles so arranged substan-

10 tially parallel with the sets of tubes as to form a plurality of vertical and connected passes for the hot gases, a combustion chamber formed in part by the fire box and having its rear wall formed by one of the

15 baffles and inclosing tubes of the first set or bank, means for introducing fuel into the fire box at a point remote from the first set or bank of tubes, and means for introducing

20 air to promote combustion, said combined fire-box and combustion chamber being of substantially uniform transverse dimensions for the entire height and having such a height as will permit a practically complete combustion of the gases, etc., before the

25 gases pass from the combustion chamber.

2. The combination with a boiler consisting of an upper and a lower drum, and a plurality of sets or banks of tubes connecting said drums, baffles so arranged substan-

30 tially parallel with the sets of tubes as to form a plurality of vertical and connected passes for the hot gases; a combustion chamber formed in part by the fire box and having its rear wall formed by one of the

35 baffles and inclosing tubes forming the first

set of banks, a stoking mechanism for feeding fuel into the fire-box at a point remote from the first bank of tubes, and means for introducing air to promote combustion said combined fire box and combustion chamber 40 being of substantially uniform transverse dimensions for the entire height and having a height approximately equal to the distance between said drums.

3. The combination with a boiler consisting of an upper and a lower drum, and a plurality of sets or banks of tubes connecting said drums, baffles extending the entire width of the boiler and projecting vertically from the respective drums for such a distance toward the opposite drums as to provide connecting throats between the adjacent 45 passes formed by the baffle; a combustion chamber formed in part by the fire box and having its rear wall formed by one of the 50 baffles and inclosing tubes forming the first set of banks, a stoking mechanism for feeding fuel into the fire-box at a point remote from the first set or bank of tubes, and means for introducing air to promote combustion, 55 said combined fire box and combustion chamber being of substantially uniform transverse dimensions for the entire height and having a height approximately equal to the distance between said drums.

In testimony whereof, I have hereunto set my hand.

WILLIAM H. RITTS.
